METAL CONTAINER

Filed May 10, 1922

FIG. 1.

FIG. 2.

FIG. 3.

INVENTOR
H. L. Steidel

BY

George W. Morlock
ATTORNEY

UNITED STATES PATENT OFFICE.

HUGO L. STEIDEL, OF BELLEVILLE, NEW JERSEY.

METAL CONTAINER.

Application filed May 10, 1922. Serial No. 559,696.

To all whom it may concern:

Be it known that I, HUGO L. STEIDEL, a citizen of the United States, and a resident of Belleville, in the county of Essex and State of New Jersey, have invented certain new and useful Improvements in a Metal Container, of which the following is a full, clear, and exact description.

Among the principal objects which the present invention has in view are: To lock the cover of metal containers in service; to provide a reliable lock for said cover secure against displacement in service; to automatically remove the cover of metal boxes when releasing the same from locked position; to provide means incorporated in the structure of boxes which operate to lift the cover from its service position when and as the same is released from its locked position; and to simplify and cheapen the construction.

Drawings.

Figure 1 is a side view of a box constructed and arranged in accordance with the present invention, the cover thereof being shown as in closed locked position.

Figure 2 is a similar view showing the cover in its released position.

Figure 3 is a top plan view of the same, the cover being partly cut away to show the construction of the container.

Description.

Though the invention herein shown is applicable to various forms and sizes of boxes adapted for containing a variety of articles, I have preferred to show the embodiment of the invention as applied to boxes of the character in which blacking or the various polishing creams are purveyed. These boxes are usually provided with a somewhat shallow body 8 to reinforce the upstanding side of which, there is provided a ridge 9.

The ridge 9 serves every purpose of forming a seat for the lower edge of the side flange 10 of the cover. The seat formed by the ridge 9 accomplishes the double purpose of limiting the fixing of the service position of the cover and of protecting the

lower generally raw edge of the flange 10 thereof.

The bead 11 may be employed or dispensed with at will. Generally the annular surface of this edge is serrated to facilitate the grip of the hand of the operator.

When constructed in accordance with the present invention, the ridge 9 is made double-ended, the ends approximating to furnish a space 12 which is occupied in service by the tongue 13. The tongue 13 constitutes both the locking element and the elevating element of the cover. To this end the recess 14 is provided at the forward end of the tongue 13 which engages in service the end 15 of the ridge 9. The lock formed thereby is sufficient to prevent the lift of a cover having the cam 16 in the flange 10, the adjustment whereof does not permit accidental disadjustment of the cover on the body of the container.

The edge of the tongue 13 is shaped to form the cam 16. The cam 16 is shaped as shown best in Fig. 1 of the drawings so that the rise of the cam begins at a distance from the end 17 of the ridge 9 equal to the depth of the recess 14. This feature of the construction permits the cover to be retractively turned a distance equivalent to the depth of said recess before the cam 16 starts to ride the end 17 of the ridge. When the cover is completely retracted the top of the cam will be seen to rest on the end 17 of the ridge 9 with the result that the cover has been substantially lifted from its active position in which it can be easily lifted from the body of the cam.

It will be understood that while I have shown the construction embodying the ridge 9, which approximately completely surrounds the body of the cam, this may be dispensed with, substituting therefor, projections to take the place of the ends 15 and 17 of the said ridge.

It will also be understood that while I have shown the invention as providing one tongue 13 and one space 12, this can be varied by employing a plurality of tongues and spaces, but I have found that for all purposes the close in the flange 10 requires

only one tongue to lock it firmly in position. Also by having the single tongue and the single opening, less care in adjusting the tongue to its service position is required than might entail in the use of more than one tongue.

When a box is constructed and arranged as herein disclosed, the operation of closing the box requires only that the cover 10 shall be adjusted in position with the tongue 13 in line with, or slightly at the rear of the space 12. When the tongue is introduced into the space 12, the rear end of the cam 16 will be found to engage the end 17 of the ridge 9. As the cover is brought to its seat where the lower edge of the flange 10 rests upon the ridge 9, it is rotated, moving the front edge of the cam toward the end 15 of the ridge. When the opening end of the recess 14 is in line with the end 15 of the ridge 9 it will be found that the full edge of the flange 10 rests entirely on the ridge 9, the cam 16 having passed completely within the space 12. The further rotation of the cover now introduces the end 15 firmly to completely fill the recess 14, the engagement thereby effected thereafter completely and perfectly locking the cover in service position.

When it is desired to remove the cover from the body of the box, this is accomplished by retractively rotating the cover. At the initiation of the retraction the tongue 13 is moved the distance of the depth of the recess 14 before the lower edge of the cam 16 engages the end 17 of the ridge 9. This insures the complete release of the end 15 of the ridge 9 by the tongue 13 and the recess 14 thereof, before the cam 16 begins the lift of the cover. From this point the continued retraction of the cover causes the cam 16 to ride over the end 17 until the position shown in Fig. 2 of the drawings is obtained. From the position thus obtained it is obvious the cover can be readily removed from the body of the cam.

It is obvious that the construction has in mind the saving in material and cost of construction. The bead 9 is usually provided and therefore the cost of construction of the body of the box is very slightly, if at all increased over the cost of the usual body of boxes. The flange 10 is upturned in the same manner as that usually employed in the construction of boxes and has the slight projection which forms a tongue 13. This tongue, together with the recess 14 is blanked in the same operation which blanks the metal from which the cover is formed, therefore, the total increase in the construction is in the amount of metal wasted in forming the blank which it will be appreciated is practically none, the tongue being so arranged as to absorb that metal which is now wastage when the circular blank from

which the cover is cut from the usual metal sheets. It will also be observed that the tongue 13 does not increase the size or space occupied by the box having no projection beyond the ridge 9 with which the box body is reinforced.

Claims.

1. A metal container comprising a body portion having a cylindrical open end; a cylindrical removable cover therefor; and means locking said cover and body in service adapted to force said cover from said container when releasing same, said means embodying a ridge spaced from the edge of said open end, and a member on said cover movable relative to said ridge for engagement therewith, said member being adapted for movement in one direction for locking said cover and body, and for movement in the opposite direction to separate said cover and body.

2. A metal container comprising a cylindrical body portion having a double ended ridge; a removable cover having means for engaging one of said ridge ends for movement thereby in opposite axial directions in correspondence with the movement of said cover in opposite rotary directions.

3. A metal container comprising a cylindrical body portion having a double ended ridge; a removable cover having means for engaging one of said ridge ends for movement thereby in opposite axial directions in correspondence with the movement of said cover in opposite rotary directions, said means embodying an integral extension arranged to extend between said ridge ends for engaging the one below the same, and the other above, for locking the cover in closed position, and for lifting it to open position, respectively.

4. A metal container comprising a cylindrical body portion having a double ended ridge thereon, a removable cover, a member carried by said cover for engaging one of said ridge ends for moving said cover axially on rotation thereof, and means on said member for engagement with the other of said ridge ends to lock the cover in position.

5. A metal container comprising a cylindrical body portion, a double ended ridge on said body portion, a removable cover, and an extension on said cover adapted to rest between the ends of said ridge for insertion below one of said ends to lock the cover, said extension being formed to ride over the other of said ends to force said cover from its seat.

6. A metal container comprising a cylindrical body portion having an open upper end, a cover therefor, a seat on said body portion for said cover and disposed below the open end of said body portion, an exten-

sion carried by said cover and adapted to engage said seat to lock said cover on the body, and means on said extension for engaging said seat to lift said cover from the body on rotation of the cover.

7. A metal container comprising a cylindrical body portion, a double ended ridge formed thereon in a plane perpendicular to the axis thereof, a removable cover adapted to seat on said ridge, an extension on said

cover to rest between the ends of said ridge, said extension being recessed at one edge for engaging one end of said ridge on rotation of the cover in one direction and cam shaped on its opposite edge for engaging the other end of said ridge to force said cover from its seat on rotation of said cover in an opposite direction.

HUGO L. STEIDEL.
